UNITED STATES PATENT OFFICE.

MARK M. DECKER, OF WASHINGTON, PENNSYLVANIA.

CAR-COUPING.

SPECIFICATION forming part of Letters Patent No. 554,336, dated February 11, 1896.

Application filed March 16, 1894. Serial No. 503,895. (No model.)

To all whom it may concern:

Be it known that I, MARK M. DECKER, a citizen of the United States, and a resident of Washington, in the county of Washington 5 and State of Pennsylvania, have invented certain new and useful Improvements in Car-Couplings, of which the following is a full, clear, and exact specification, such as will enable others skilled in the art to which it app-10 pertains to make and use the same.

My invention relates to that class of car-couplings in which a swinging locking-jaw is pivoted in a bifurcated draw-head, and is made to swing inside said head and become 15 locked therein by the impact of the coupling on another car.

My invention consists of an improved car-coupling provided with a swinging locking-jaw mounted in a bifurcated draw-head and 20 a locking and releasing pawl and devices for operating said jaw and pawl.

One form of my invention is shown in the accompanying drawings, in which—

Figure 1 is a perspective view showing the 25 coupling with the parts in the coupled position. Fig. 2 shows a pair of couplings, one in plan and the other in horizontal section, illustrating the parts in the coupled position. Fig. 3 is a horizontal sectional view showing the 30 parts in the uncoupled position. Fig. 4 is an inverted plan view of the locking-jaw, showing the recessed incline therein. Fig. 5 is a perspective side elevation in detail of the pin for holding and operating the locking-pawl, and Fig. 6 is a perspective view of the locking-pawl. 35

Similar letters indicate corresponding parts in the different drawings.

A is a bifurcated draw-head of usual construction; B, the locking-jaw, and C the locking and releasing pawl.

The jaw B is mounted in the head A and pivoted at a. The noticeable features of this jaw are, first, the beveled locking-face b, which 45 enables the operator to release or unlock the jaw under a greater strain than could otherwise be done, and, second, the recessed incline b' in the under side of the jaw, which corresponds with the incline b'' on the lower hinge-pintle of the head. 50

The locking and releasing pawl C is hung inside of the bifurcated head A on the pivot c

which passes through the top and bottom wall of the head, and is provided at its upper end with an inclined head d, which corresponds 55 with an incline e, concentric with the pin-hole c' in the top of the head A. As can be seen by reference to the drawings, the pawl C, by means of these inclines d and e, will have a tendency to fall and be held in the locked position at all times, other than when it will be crowded back by the closing or releasing of the locking-jaw B. When said jaw moves inward, the locking portion f will strike against the pawl C, crowding it back until it reaches 60 a point where the locking portion will have passed the pawl, when said pawl will fall in front of the said locking portion and lock the jaw in the closed position.

The pawl C, as before stated, is provided 70 with a beveled locking-face g, which corresponds with the locking-face b of the locking-jaw B. By means of these beveled locking-faces b and g of the locking jaw and pawl the operator is enabled to unlock or release 75 the jaw B under a greater strain than could be done otherwise. The backward or inward movement of the pawl is brought about by a chain, or its equivalent, which may be attached at or near the forward or locking end 80 of the pawl C and passing up through a hole h in the top of the head; or an operating-lever may be connected direct with the pivot-pin of the locking-pawl C or in any other suitable manner. As soon as the chain or 85 lever is released, the pawl returns to its normal position under the attraction of gravity. The broken lines, Figs. 2 and 3, denote the paths of the moving parts—to wit, the locking jaw B and pawl C. 90

The incline b'' is formed on the lower hinge-pintle of the head, concentric with the pin-hole, and the corresponding recessed incline b' is formed in the under side of the locking-jaw B, the purpose of these inclines b' and b'' 95 being to lift the jaw vertically while closing, so that when it is released it will fall into the uncoupled position relative to the draw-head.

The operation is as follows: Before coupling, the pawl C is in the position shown in Fig. 2, but the locking-jaw is outside of the draw-head in position to be struck by a corresponding locking-jaw on another car, whether in a locked or unlocked position. As soon as the

- locking-jaw B is struck by this other coupling, it moves back into the head, crowding the pawl C out of the way until the locking-face *b* has passed the face *g*, at which time the locking-jaw B has taken the position shown in Fig. 3. The pawl C, no longer having any pressure upon it, falls back in front of the locking portion of the jaw and locks it in the coupled position, as shown in Fig. 2.
- 10 The coupling is unlocked, as before stated, by drawing back on the chain or lever. The chain is then released and the pawl returns to its normal position.
- Having described my invention, what I
15 claim is—

In a car-coupling the combination of a bifurcated draw-head having an incline on its lower hinge-pintle and a locking-jaw provided with a recessed incline in its under side concentric with the hinge-pin of said jaw and 20 corresponding with the incline on the said lower hinge-pintle, of a locking-pawl mounted inside the head on a pin provided at its upper end with an inclined head corresponding with an incline formed on the top of the head, substantially as shown and described.

MARK M. DECKER.
